Atty.

UNITED STATES PATENT OFFICE.

HENRY K. SANDELL, OF CHICAGO, ILLINOIS, ASSIGNOR TO HERBERT S. MILLS, OF CHICAGO, ILLINOIS.

SOUND-MODULATING DEVICE.

1,361,500.

Specification of Letters Patent. Patented Dec. 7, 1920.

Application filed February 26, 1920. Serial No. 361,382.

To all whom it may concern:

Be it known that I, HENRY K. SANDELL, a citizen of the United States, residing at Chicago, in the county of Cook and State 5 of Illinois, have invented a new and useful Improvement in Sound-Modulating Devices, of which the following is a specification.

The present invention relates to devices 10 for modulating the tone emitted by sound reproducing devices of the phonograph or gramophone type, wherein the desired sounds are produced by the vibration of a resiliently held diaphragm. It will be 15 clearly understood from the following description thereof, illustrated by the accompanying drawings, in which—

Figure 1, is a side elevation of a phonograph tone arm provided with a sound box 20 containing a vibrating diaphragm and provided with a modulating device constructed in accordance with the present invention.

Fig. 2, is a sectional view on enlarged scale through the sound box of Fig. 1.

Fig. 3, is a broken sectional view on line 25 3 of Fig 2, and

Fig. 4, is a detail view of an element of the modulator construction.

Referring now particularly to the drawings, the numeral 5 indicates a tone arm 30 provided with a pivotally mounted stylus holder 6, the vibrations of which are communicated by means of the transmission member 7, to diaphragm 8, mounted in sound box 9, as now particularly described in my first Patent No. 1325209 of Dec. 6, 1919. A spider 10 is united with the sound box 9, serving in the construction to rigidly connect the tone arm 5 therewith. The 35 sound box is connected through conduit section 11 with conduit joint 12, which is rotatably mounted on the support 13.

Vibration transmission member 7 is firmly attached to diaphragm by means of pin 14, 40 a washer 15, being provided between the head of the pin and the under side of the diaphragm. A fine wire or pin 16, is attached to the diaphragm at approximately its center, for example, by soldering to the 45 end of the pin 14, as at 17. This pin extends from the diaphragm through a bushing 18 50 of yieldable material, such as soft rubber,

which is set into a split cap 18 retained in a suitable opening provided in the spider 10 by means of a set screw 19. As shown 55 in Fig. 4, the cap 18 is provided with diametrically opposite slots 20 extending nearly to its closed end.

The sound emitted by the diaphragm is modulated by adjustment of the screw 19. 6 By tightening the screw the yieldable bushing is compressed about the pin and the friction to be overcome by the modulating pin in its movement is increased, and the tone emitted is correspondingly softened. 6 By loosening the screw the loudness of tone is increased.

Although in the description of the present invention a specific detail of construction has been illustrated, it is not intended that 70 these details shall be regarded as limitations upon the scope of the inventor, except in so far as included in the accompanying claims.

1. In combination, a sound box diaphragm, means for producing vibrations 75 thereof, a modulating pin attached to said diaphragm and extending perpendicularly therefrom, a yieldable bushing surrounding said pin and adjustable means for compressing said bushing. 80

2. In combination, a sound box, a diaphragm mounted therein, means for producing vibrations of the diaphragm, a modulating pin attached centrally to said diaphragm and extending outwardly therefrom, a supporting member mounted on the sound box and provided with an opening into which the pin extends, a yieldable bushing surrounding said pin, a split cap 85 surrounding said bushing and a set screw 90 mounted in said support for compressing the cap and bushing.

3. In combination, a sound box, a diaphragm mounted therein, means for producing vibrations of the diaphragm, a 95 modulating pin attached centrally to said diaphragm and extending outwardly therefrom, a supporting member mounted on the sound box, and provided with an opening into which the pin extends, and means supported on said supporting member for producing variable friction upon said pin. 100

HENRY K. SANDELL.
